UNITED STATES PATENT OFFICE

2,618,399

RIVET DETONATING TOOL

William C. Stratman and Joseph W. Fischer, Los Angeles, Calif., assignors to North American Aviation, Inc.

Application August 6, 1949, Serial No. 109,014

2 Claims. (Cl. 218—19)

1

This invention pertains to a device for detonating explosive rivets. Rivets of this type are well known in the art and constitute, generally, an arrangement whereby blind riveting can be accomplished by the use of an explosive charge contained within the rivet. Difficulty has been experienced in satisfactorily detonating these rivets to the extent that it is now common practice to use soldering irons and blow torches for that purpose. This is an expensive and somewhat dangerous expedient and, accordingly, it is an object of the present invention to provide a mechanism by which these rivets can be detonated easily and quickly.

It is another object of this invention to provide an arrangement which is quite effective and yet safe from an operative standpoint.

It is yet another object of this invention to provide a rivet detonator which is relatively inexpensive, easy to maintain, and of long life.

Other objects of invention will become apparent from the following description taken in connection with the accompanying drawings, in which

Fig. 1 is an elevational view of a rivet gun incorporating the present invention, and

Fig. 2 is a sectional view of the rivet-holding and detonating part of the gun taken at line 2—2 of Fig. 1.

Referring to the drawings, 1 and 2 represent plates or sheets of material which are to be fastened together by rivet 3 of the explosive type. To accomplish detonation of the rivet, gun 4 is adapted to hold the rivet in place and at the same time impart to it a high frictional force such as will cause detonation. Gun 4 may be essentially a high-speed air-driven rotary drill motor capable of producing approximately 20,000 revolutions per minute. The details of the operating mechanism of the motor which produces rotary motion are not shown because they are conventional in the art. For the purposes of this invention, however, this gun includes a chuck 5 for drivingly holding a spindle 6 mounted rotatably in member 7, which in turn carries collar 8 and is integral with casing 9. Casing 9 is carried by forward extension 22 of the casing of gun 4 and is connected thereto by a nut 21 in a manner well known in the art. Casing 9 may be provided with slits at the end thereof to contract it upon member 22 as is customary in this art if desirable or necessary to attach casing 9 to 22. Casing 9 may also be provided with a window 20 for purposes of using a chuck key on chuck 5 to fasten or unfasten spindle 6 in the chuck, all in a man-

ner common to the art. A sleeve 10 is slidably received in member 7 and held against rotation by ball 11 located in recess 12 of member 7, and slot 13 of sleeve 10. A recess 14 is provided in collar 8 to permit assembly and disassembly of this arrangement by forward movement of member 7 with respect to collar 8 to permit ball 11 to be received in recess 14, thereby permitting sleeve 10 to be withdrawn from member 7. Ring 15 limits inward movement of member 7 on collar 8. Springs 16 and 17 hold the various parts in extended adjusted position. Sleeve 10 may be provided with a tip 18 of phenolic or fibrous material for better holding the rivet in position, although it is to be understood that this tip can be omitted if desired. Spindle 6 is also provided with a tip 19 of phenolic or other material having a high coefficient of friction for the purpose of better detonating the rivet 3. This tip may be omitted if the spindle is made of suitable material.

In the operation of the arrangement, rivet 3 is placed by hand, or otherwise, in aligned openings in members 1 and 2, whereupon the tip 18 of gun 4 is brought into contact with the head of the rivet to hold it in place. Thereupon the body of the gun is pressed forwardly to cause relative retraction of sleeve 10 against spring 17 to bring the tip 19 of spindle 6 into engagement with the head of rivet 3. High-speed rotation of spindle 6 and tip 19 results in the generation of sufficient heat to cause detonation of the rivet. The holding of the rivet firmly in place while being detonated insures a proper seating of the rivet, prevents rotation of the rivet and consequent scoring of the material being fastened, and affords a safety feature to the operator. Spring 17 is designed to resist a predetermined force such as will properly hold the rivet in place against rotation when engaged by tip 19, and to firmly seat the rivet to insure proper functioning thereof when exploded.

It is to be understood that the detonating gun may take other forms and shapes and that, although the invention has been described and illustrated in detail, the same is by way of illustration and example only, and is not to be taken by way of limitation, the spirit and scope of this invention being limited only by the terms of the appended claims.

We claim:

1. A rivet detonating tool for use with a drill motor having a fixed casing and a relatively rotatable chuck, a sleeve slidably carried by said casing, a tip having a high coefficient of friction

2

carried by and rotatable with said chuck, and spring means urging said sleeve outwardly beyond said tip to seat and hold an explosive rivet, said sleeve being retractable against the action of said spring to allow said tip to rotatably engage said rivet to heat the same and thereby explode the same as the result of the heat produced by the friction of said tip upon said rivet.

2. A device as recited in claim 1 in which said tip is formed of phenolic material.

WILLIAM C. STRATMAN.

JOSEPH W. FISCHER.
